UNITED STATES PATENT OFFICE.

GEORGE W. McLEAN AND EDWARD J. SHUR, OF NEW ORLEANS, LOUISIANA.

CHECKING DEVICE.

1,383,834.

Specification of Letters Patent.

Patented July 5, 1921.

Application filed November 22, 1919. Serial No. 339,793.

To all whom it may concern:

Be it known that we, GEORGE W. McLEAN and EDWARD J. SHUR, both citizens of the United States, both residing at New Orleans, in the parish of Orleans and State of Louisiana, have invented new and useful Improvements in Checking Devices, of which the following is a specification.

Our present invention pertains to checking apparatus, and it contemplates the provision of a device whereby a person passing through the same will register such fact and hence when used as an adjunct to a freight car, ship or the like the number of trips made by a person into such places will be accurately indicated on the register of the device and hence the necessity of employing a checker or other attendant will be obviated. By the use of the apparatus the well known short count by unscrupulous checkers will be prevented and the efficiency of a certain shift of employees or laborers may be accurately ascertained; and moreover when used during the loading of bananas, the number of bunches of bananas carried into the ship will be always apparent, especially in view of the fact that each laborer generally carries but a single bunch of bananas on each trip into the ship.

The invention in all of its details will be fully understood from the following description and claims when the same are read in connection with the drawings, accompanying and forming part of this specification, in which:

Figure 1 is a perspective view of our novel device, showing the platform and checking apparatus arranged thereon.

Fig. 2 is a section of the shaft on which the checking arm revolves and also showing the pins that limit the movement of the checking arm.

Fig. 3 is a longitudinal section of the shaft and cross-arm and showing the connection of the checking arm.

Fig. 4 is a detail view of the checking arm and spring clip for restricting movement of the said arm.

Similar numerals of reference designate corresponding parts in all of the views of the drawings.

Our novel device is mounted or otherwise secured on a portable platform 1 that is equipped with the runway 2 and is mounted on the legs 3 whereby the platform may be placed alongside a car door or the like; it

being well to bear in mind that the runway will be placed parallel with respect to the car or car door opening. It is well to bear in mind however, that the platform may be equipped with legs as in the present instance or with other means to elevate the platform in the discretion of the manufacturer.

As illustrated in the drawings, the platform is equipped with a rail 4 on which the hooks of the runway will rest, and arranged on the platform we provide a passageway formed by the upstanding frames 5 and 6. The frames 5 and 6 are preferably arranged on the platform as illustrated and in this connection it will be apparent that the frame 5 does not extend to the full depth of the platform. We make this provision so that a laborer may turn to the left at the second upright and travel in the direction of the arrow. The side A of the platform is placed against the opening of the warehouse, car or the like to be loaded and when the laborer has attended to his mission in the warehouse or the like he will return in the direction of arrow B and thence down a runway, (not shown) similar to the runway 2 that is arranged on the long rear side of the platform 1. The frame 6 has the runners 7, 8, 9, 10, 11, 12 and 13 and 14 and secured between the runners 7 and 8 is our novel checking apparatus.

The said apparatus comprises a checking arm having an end 15 that normally extends across the passageway between the frames 5 and 6. The said end 15 is threaded or otherwise secured to a rotatable cross piece 16 that is movable around a shaft 17 that in turn is mounted in blocks 18 and 19. These blocks 18 and 19 are screwed or otherwise fastened into the runners 7 and 8, respectively of the frame 6.

On the opposite side to that in which the checking arm 15 is secured in the cross piece 16, we thread a short arm 20 that is slightly reduced in size at its outer end as appears in Fig. 3 for an important purpose hereinafter set forth.

As will be seen by reference to Fig. 1, the post 21 of the frame 6 is provided with a spring clip comprising spring leaves 22 and 23 that are secured to the post 21 by interposing plates 24 and 25 between the inner ends of the leaves and then passing pins 26 through the leaves and plates. At their outer ends the leaves form a substantial Y, and the upper leaf 22 is provided at a point

slightly in rear of the Y with a recess 27, Fig. 4, to receive the slightly reduced end of the arm 20. The leaves are further held in proper positions by the bolt 28.

5 Secured to the outer end of the arm 20 is a chain 29 that passes over a pulley 30 and is secured to a chain that in turn connects with the ordinary well-known register 31, such as for instance those used in a street 10 railway car.

In order to prevent the arms 15 and 20 from turning farther than necessary about the shaft 17, we provide between the blocks 18 and 19 and at either side of the cross arm

15 16, the stop pins 32 that by preference are covered with rubber tubing 33. (See Fig. 2).

In the practical use of the device the platform is placed with the side A abutting a car door opening or the like with the 20 runway 2 in its proper position on the rail 4 of the platform.

When a laborer carrying merchandise or the like enters the passage way between the frames 5 and 6, his body will strike the 25 checking arm 15 which will move in the same direction in which the person is traveling. Naturally the cross-piece will rotate on the shaft 17 and move the arm 20 out of the recess 27 of the leaf 22 and in the direction opposite to that of the arm 15. The chain 29 being attached to the arm 20 will be placed under tension and pulled forward thereby causing the register to operate and register the passage of the laborer or other 30 35 person through the device. The arms 15 and 20 will be limited in their movements not only by the spring 29 but also by the rubber covered pins 32. Said pins 32 will, because of their resilient covering assist the spring 40 45 to quickly return the said arms 15 and 20 to their normal positions, after the body of the person has released the arm 15. The recess 27 will tightly hold the arm 20 against casual movement and the clip will prevent a 50 55 person from attempting to return through the passage way.

Of course it is obvious that the arms 15 and 20 may be placed at any point throughout the height of the frames, and in fact 50 as many arms 15 and 20 may be used to pre-

vent a person from crawling under or climbing over the arm 15 and thus fail to register his entry into the ship or car.

We would have it distinctly understood that the arms, clip and cross-arm as well as 55 any other elements of the device may be formed of wood or metal as occasion demands.

The device as a whole is simple in construction and very inexpensive to produce 60 and maintain and will eliminate the requirement for a checker and will also be reliable in its recording which is not the case where an attendant is employed.

Such changes in the relative size and arrangement of parts may be made as fairly fall within the scope of the appended claims.

Having described our invention, what we claim and desire to secure by Letters-Pat- 70 ent, is:

1. In a checking device, the combination of a revolute member, pins adjacent the revolute member, a checking arm having one end secured to the revolute member, an arm secured to the revolute member directly 75 in rear of the checking arm, a register communicating with and actuatable by movement of the arms; said arms being limited in their movements in one direction by the pins adjacent the revolute member, and a spring 80 clip so constructed and arranged with respect to the second arm that it limits the movement of the checking arm and second arm in another direction.

2. In a checking device, the combination 85 of a revolute member, arms secured to the revolute member and movable therewith, a register communicating with the arms, pins for limiting the movement of the arms in one direction, and a clip that 90 prevents movement in the opposite direction.

In testimony whereof we have hereunto set our hands in presence of two subscribing witnesses.

GEORGE W. McLEAN.
EDWARD J. SHUR.
